MEANS FOR FASTENING MATERIAL TO
STRUCTURAL IRON FRAMEWORKAndrew B. Hammitt and Herbert L. Birum, Jr.,
Trenton, N. J.

Application August 13, 1948, Serial No. 44,024

4 Claims. (Cl. 189—35)

1

This invention relates to fastening means for securing sheet material to the structural framework of a building, and is directed particularly to constructions for use in securing corrugated sheets of cement asbestos material to structural iron framework.

One of the most common forms of fastening means heretofore employed in securing sheet material to framework embodies a bolt which extends through the sheet material and over a face of the structural iron beyond the opposite edge of the framework element. A toe clip or other member formed with a hook-shaped end extends about a flange on the framework and is provided with an opening through which the bolt extends to hold the toe clip in firm engagement with the framework element and to draw the sheet material into firm engagement with the opposite side of the framework. Constructions of this type are objectionable because the projecting inner end of the bolt interferes with the stacking of goods close to the walls of the building. In fact, such projecting bolts present a serious hazard to anyone passing close to the walls and frequently tear clothing or injure persons. The bolts themselves may be bent or broken by heavy boxes, or hand trucks which are moved up against the inside walls of the building. Prior constructions are also objectionable because of their unattractive appearance and the difficulty encountered in painting over surfaces from which such bolts project.

Moreover, the toe clip or other member which engages the framework does not engage the sheet material and therefore does not always insure a tight construction. This is particularly true when the framework element is wide and relatively long bolts are employed to span the framework. Such bolts are easily bent or may be laterally displaced on the framework by a careless worker. The toe clip or hook-shaped member engaged by the bolt also tends to bend into a tilted position when the sheet material is drawn up tight resulting in a loose or weakened construction.

Another objection to constructions of the prior art results from the fact that fastening means cannot be used satisfactorily when insulating material or covering is applied to the inner face of the roof or wall to which the sheet material is secured.

In accordance with the present invention, these objections to constructions of the prior art are overcome by providing a novel type of fastening means wherein the bolts used in securing sheet material to a framework are hidden or protected by the framework itself. Those elements which

2

engage the framework present a smooth and preferably flat exposed surface which lies closely adjacent the inner surfaces of the framework. The fastening means of the present invention further include means which are engageable with both the framework and the sheet material and are so formed that the strength and rigidity of the assembly is increased as the element is drawn more firmly into place.

One of the objects of the present invention is to provide novel fastening means for securing sheet material to structural iron framework of a building which are neat and attractive in appearance and eliminate dangerous or undesired projections on the interior of the building.

Another object of the present invention is to provide a novel type of fastening means which is engageable with both the framework and a sheet of material in a manner to insure firm contact therewith.

Another object of the invention is to provide fastening means for sheet material wherein the operation of tightening the element serves to increase the strength and rigidity thereof.

These and other objects and features of the present invention will appear from the following description thereof in which reference is made to the figures of the accompanying drawing.

In the drawing:

30 Fig. 1 is a vertical sectional view through a building framework and sheet material having a typical form of fastening means embodying the present invention applied thereto.

Fig. 2 is a perspective of a portion of a building framework and sheet material embodying the construction illustrated in Fig. 1.

Fig. 3 is a horizontal sectional view of the construction shown in Fig. 1 taken on the line 3—3.

Fig. 4 is a vertical sectional view through a framework element and sheet material illustrating an alternative form and application of the present invention.

In that form of the invention chosen for purposes of illustration in Figs. 1 to 3, the sheet material is indicated at 2 and is secured to the outer face of a framework element 4 which as shown is in the form of a downwardly facing channel iron. The outer flange 6 of the channel iron 4 is engaged by the inner extremities of the convolutions 50 of the corrugated sheet material 2. The web 8 of the channel iron faces upwardly whereas the inner flange 10 of the element 4 is spaced inward from the flange 6 and extends downward.

The fastening means of the present invention embodies an element 12 provided at its inner extremity with a hook-shaped portion 14 of such

3

size and shape that it will extend inward and upward behind the lower edge 16 of the flange 10 while the portion 15 thereof lies flat against the inner face of flange 10 of the element 4. The part 18 of the fastening element extends outward from portion 15 and is also flat and formed to bear against the upper face of the web 8 of the structural element 4. The part 18 preferably extends outward to a point adjacent the outer face of the flange 6 and then extends upward at right angles to present a bolt receiving portion 20 provided with an opening 22 through which a bolt 24 is passed. The end of the element 12 which extends above the upper edge of the bolt receiving portion 20 is inclined outward as shown at 26 into position to be brought into engagement with the inner face of the sheet 2 as the nut 28 is drawn up on bolt 24. The end 26 preferably has an edge which presents corners 30 that are relatively sharp and tend to dig into the sheet material as the nut 28 is tightened.

The outer end of the bolt 24 is provided with a head 32 which bears against a washer 34. The washer, in turn, is pressed against a sealing member 36 formed of lead or other malleable or deformable material for sealing the opening 38 in the sheet material through which the bolt 24 extends.

As shown in Figs. 2 and 3, the fastening element 12 is preferably in the form of a flat strip of metal and the corners 30 of the inclined end 26 therefore dig into the sheet material in a manner to prevent undesired bending of the bolt receiving portion 20 even when the nut 28 is drawn up forcibly along the bolt 24. The element engages both the sheet material 2 and the structural element 4 whereby all looseness due to bending or displacement of the bolt is eliminated. The flat surfaces thereof insure contact with the framework over an extended area and aid in seating the fastening element by conforming to the surfaces engaged. Furthermore the fastening elements may be made in any of various sizes to permit application thereof to different sizes of structural iron while using the same bolts throughout the assembly.

In applying the fastening element of the construction shown in Figs. 1 to 3, the hook-shaped end 14 of the fastening element 12 is passed inward about the lower edge 16 of the flange 10 while the element itself is held in a tilted position. Thereafter, the outer end of the fastening element is swung outward and downward so as to bring the flat portion 15 into contact with the inner face of flange 10 and to bring the flat part 18 in contact with the upper surface of web 8 of the framework element 4. The bolt 24 is then inserted through the opening 38 in the sheet material 2 and the inner end of the bolt is passed through the opening 22 in the bolt receiving portion 20 of the fastening element. Nut 28 is applied to the bolt 24 and is drawn up tightly to pull the sheet material 2 inward against the outer face of the flange 6 of the structural element. At the same time inclined end portion 26 is forced outward until the corners 30 thereof are caused to engage the inner face of the sheet material in a manner to support the upper edge of the bolt receiving portion 20.

With this construction the bolt receiving portion 20 and the inner end of bolt 24 are spaced outward from the inner face of the flange 10 of the structural element. They are thus hidden or protected from injury and dangerous projections are eliminated so that they will not interfere with the stacking or movement of goods close to the

4

walls of the building. The flat portion 15 which extends parallel to the inner face of flange 10 of the element 4 presents a smooth surface which fits snugly against the flange presenting a neat, clean appearance. Moreover in applying the fastening means the bolt serves to draw the portion 15 and hook-shaped end 16 tightly against the framework so as to cause the element to substantially conform to the surfaces it engages insuring firm contact therewith. At the same time, when nut 28 is drawn up against the bolt receiving portion 20 the edge 36 of the inclined end 26 is pressed against the inner face of the sheet 2. The portion 26 then serves to support the upper edge of portion 20 and holds it in place. Thereafter further tightening of nut 28 tends to force the flat part 18 which is connected to the lower edge of portion 20 in a direction downward into firm engagement with the upper face of web 8 of element 4. Such downward movement of portion 18 is increased by any bending of the extremity 26 about its corners 30. In this way, the fastening element is seated securely in place and it is strengthened as the bolt is tightened. In actual practice it is found that the nut may actually be drawn up with sufficient force to crack the cement asbestos sheet material without producing any distortions or bending of the fastening element which would seriously weaken the assembly. The sheet material therefore may be secured in place with sufficient force to insure the most effective and firm attachment thereof to the framework.

An important feature of the present construction is the obtuse angularity of the end portion 26 with respect to the bolt receiving portion 20. Such angularity not only tends to draw the portion 18 down against the upper face of the web 8 of element 8 as mentioned above but provides a strengthening of the unit by resisting turning moments between the portion 20 and the part 18. As distinct from a right angular bend which would provide for right angular abutment with the material lending no support to the material and which would tend to buckle under the portion 20 to apply the full load of the bolt strain at the juncture of portions 20 and 18, the present obtuse angularity acts to provide an acute biting angularity of engagement of the end with the material and resists any bending moment between the portions 18 and 20. It will of course be observed that as the bolt is tightened the whole assembly is tensioned and that the tightening force tends to bend back the bolt receiving portion 20 against the flat portion 12 while the direct pressure of the nut tends to bend such portion outwardly. Obviously such forces react and neutralize to effect a resultant strength at this otherwise vulnerable bend in the fastener.

In that form of the invention illustrated in Fig. 4, a modified shape of fastening element is employed for use in securing sheet material to an angle iron type of structural framework element. In this construction the inner hook-shaped end 40 of the fastening element 42 extends about the inner edge 44 of the inwardly extending flange 46 of the structural iron framework element 48. The flat part 50 of the fastening element extends across the upper face of the flange 46 to the outer face of the downwardly turned flange 52 of the angle iron framework element. The bolt receiving portion 54 and the inclined end 56 of the fastening element are similar in construction and function to the portions 20 and 26 of the type of fastening element illustrated in Figs. 1 to 3. The bolt 24 and the

nut 28 of this assembly are identical with those employed when using the fastening element 12 of Fig. 1. It is thus possible to use the same nuts and bolts throughout while using different types of fastening elements in the roof or siding of a building. In each case the fastening element is brought into firm, rigid engagement with both the structural element and the sheet material and the bolt is supported in a manner which prevents tilting or bending of the bolt, or undesired relative movement of the sheet material with respect to the framework.

While typical forms of fastening elements and assemblies embodying the present invention have been illustrated in the drawing and described above for the purposes of indicating the nature of the present invention, it will nevertheless be apparent that the form, construction and arrangement of the elements employed may be varied considerably in adapting and using the present invention in connection with other types, sizes and shapes of structural iron framework or sheet material. In view thereof it should be understood that the particular embodiments of the present invention shown in the drawing are intended to be illustrative only and are not intended to limit the scope of the invention.

We claim:

1. A building embodying a structural iron framework element with sheet material applied thereto and secured in place by means of a bolt and a fastening element, said fastening element being formed of resilient material provided on one end with a hook-shaped portion engaging the framework element and formed on the other end with a bolt receiving portion presenting an outwardly directed obtusely inclined extremity engaging the inner face of the sheet material at an acute angle and holding said bolt receiving portion in a position substantially parallel to the sheet material, said bolt passing through the sheet material and bolt receiving portion of the fastening element, and a nut on the bolt engaging the bolt receiving portion and forcibly urging the fastening element into engagement with the sheet material and framework element whereby the bolt is assisted in its support of the material by the acute engagement of the material by said extremity and whereby said extremity will resist outward bending moments of the bolt receiving portion.

2. A building embodying a structural iron framework element with corrugated sheet material applied thereto, said framework element having a flange spaced from the sheet material, a fastening element formed of resilient metal having a hook shaped portion embracing said flange, a body portion to which said hook shaped portion is connected extending over a face of the framework element toward the sheet material, the end of the body portion adjacent the sheet material extending at right angles to the body portion and having a bolt receiving opening therein, an extremity of said right angularly extending portion being obtusely inclined outward beyond the framework and into one of the corrugations in the sheet material so as to engage the inner surface of the sheet material at an acute angle, a bolt extending through the sheet material and through said opening in the right angularly extending portion, and a nut engaging the bolt and the right angularly extending portion serving to urge the hook shaped portion into clamping engagement with said flange and to urge said extremity of the right angularly ex-

tending portion into bracing engagement with the sheet material whereby the bolt is assisted in its support of the material by the acute engagement of the material by said extremity and whereby said extremity will resist outward bending moments of the bolt receiving portion.

3. Means for securing sheet material to the structural framework of a building comprising a member formed of resilient material and provided at one end with a hook-shaped portion for engagement with an element of a building framework and having a flat portion connected to said hook-shaped portion for engagement with a surface of said element, said member being provided with a bolt receiving portion extending substantially at right angles to said flat portion and having an opening therein for receiving a bolt, the opposite end of said member projecting at an obtuse inclination from the bolt receiving portion and away from said hook-shaped portion so that when said member is applied to a framework element and secured in place by a bolt passing through a sheet of material adjacent said element and through said opening in the bolt receiving portion of the member said opposite end will be urged outward and upward against the sheet material in a manner to aid in supporting the sheet material and will at the same time oppose outward bending of the bolt receiving portion when the bolt is tightened in securing the sheet material, member and framework element together in assembled relation.

4. Means for securing sheet material to the structural framework of a building comprising a flat strip of resilient metal formed on one end with a hook-shaped portion for engagement with an element of the building framework and having a flat portion adjacent to said hook-shaped portion for engagement with a surface of said element, said strip being provided with a bolt receiving portion extending substantially at right angles to said flat portion and having an opening therein for receiving a bolt, the opposite end of said strip extending at an outward obtuse inclination from the upper extremity of the bolt receiving portion and in a direction away from the hook-shaped end of the strip so that when said member is applied to a framework element and secured in place by a bolt passing through a sheet of material adjacent said element and through said opening in the bolt receiving portion of the member said opposite end will be urged outward and upward against the sheet material in a manner to aid in supporting the sheet material and will at the same time oppose outward bending of the bolt receiving portion when the bolt is tightened in securing the sheet material, member and framework element together in assembled relation.
